UNITED STATES PATENT OFFICE.

WILLIAM FRED DUNNING, OF WASHINGTON, DISTRICT OF COLUMBIA.

LOOSE-LEAF BINDER.

1,398,422.

Specification of Letters Patent. Patented Nov. 29, 1921.

Application filed August 24, 1920. Serial No. 405,649.

To all whom it may concern:

Be it known that I, WILLIAM FRED DUNNING, a citizen of the United States, and resident of the city of Washington, in the District of Columbia, have invented certain new and useful Improvements in a Loose-Leaf Binder, of which the following is a specification.

My invention relates to a loose leaf binder, 10 and more particularly to a loose leaf binder to hold individual loose sheets, and so constructed as to permit ready access to any of said sheets.

A binder constructed in accordance with 15 my invention will permit any number of individual sheets or cards, within the capacity of this device, to be securely fastened and at all times permit ready removal of any sheets or cards without displacing the remaining 20 ones.

One object of my invention is to provide a binder which employs straight prongs or binding posts. Various advantages are present in a device with straight binding posts 25 which are not realized in the type of binder now universally used in which curved binding posts or pins are employed.

Another object of my invention is to provide 30 a binder which will be automatic in its action; *i. e.*, will be capable of being locked only when the binding posts or pins are in proper alinement with the apertures of sheets or cards inserted in the binder.

Various other advantages will be made 35 more apparent in the specification and in the drawings, in which—

Figure 1 is a fragmentary perspective view of the binder in open position,

Fig. 2 is a rear elevation of the back of 40 the binder in open position,

Fig. 3 is a sectional view taken on line 3—3 of Fig. 2,

Fig. 4 is a vertical transverse section of the 45 binder in closed or locked position,

Fig. 5 is a section taken on line 5—5 of Fig. 4,

Fig. 6 is a front elevation of the back of 50 the binder in open position, and

Fig. 7 is a horizontal section taken on line 55 7—7 of Fig. 5.

Referring now more particularly to the drawings in which 10 indicates the sides or covers of the binder, and 11 metallic strips disposed adjacent one end of each of the 55 cover pieces 10. These metallic pieces may be connected in any suitable manner to the

cover pieces 10 which will provide a flexible connection, and I have here illustrated this connection being made by the linen covering of the binder which will extend around the 60 cover pieces 10 and the metallic strips 11 and across the back of the device as indicated at 12, providing a covering for the working parts thereof.

Adjacent the back of the binder to which 65 this invention relates, there are transversely disposed plates 13 secured in any suitable manner to the metallic strips 11. Secured to these plates 13 are binding posts or pins 14. These binding posts or pins are straight and 70 project right-angularly from the plates 13. The posts on the opposite plates are offset from one another to enable them to come into alinement with the series of apertures contained in the leaves or sheets used in connection with binders of this type.

The inner edge of each of the plates 13 is provided with curved lips 15 which encircle hinge rods 16. Right-angular lips or projections 17 are also formed on the inner edge 80 of each of the plates 13. All of this is for a purpose to be more fully hereinafter described.

A pair of sliding back-plates 18 have similarly formed curved lips 19, which encircle 85 the hinge rods 16 to hingedly connect each of the plates 13 with one of the sliding back-plates 18. This is clearly illustrated in Figs. 1, 2 and 3. The back plates 18 are provided with recesses, or cut-out portions, 20 to accommodate the right-angular lips 17. It is apparent that while the hinge connection between the plates 13 and 18 allows relative movement thereof, this movement is limited in one direction by the angular lips 17 coming in contact with the sliding back-plates 18. When these lips 17 are in contact therewith, the plate 13 and the appurtenant parts thereto are at right angles to the back of the binder and the pins 14 are vertically disposed 90 and in alinement with the apertures of the sheets or cards. In this connection the metallic strips 11 are extended beyond the hinged connection between the plates 13 and 18 as indicated at 21 and thereby afford a 95 stop for the covers or sides of the device in the other direction.

Extending longitudinally of the back is a pair of locking plates 22 which cover the overlapping edges of the sliding back-plates 110 18. The sliding back-plates are each provided with a pair of vertically disposed slots

23 and passing through these slots are studs 24, which studs are rigidly secured in the pair of locking plates 22. These studs, therefore, provide guide members for the 5 movable back plates 18 and limit the travel of these back plates, in a manner to be more fully hereinafter described.

The vertical edges of the pair of locking plates are provided with cut-away portions 10 or locking recesses 25, while the vertical edges of the sliding back-plates 18 are provided with locking notches 26 and beveled surfaces 27.

Mounted upon the rear plate of the pair 15 of locking plates 22 is the locking mechanism. This comprises two longitudinal locking bars 28 provided near their outer ends with slots 29 through which pass studs 30. These studs 30 are rigidly mounted in 20 the rear locking plate 22 and provide a guide for the outer end of each of the locking bars 28. The inner ends of the locking bars are pivoted as at 31 to a link 32 pivoted as at 33 to the locking plate 22. A coil spring 25 34, or spring of any other suitable nature, has its ends connected to one of the lockbars 28, as indicated at 35 and to an intermediate portion of the other locking bar, as indicated at 36. This spring, therefore, retains 30 the locking bars in the position illustrated in Fig. 2 in which position they are at the limit of their inward travel, and are in locking position. The outer end of each of the locking bars 28 is provided with a right- 35 angular projection or latch 37 which lies within one of the recesses 25 at each end of the locking plates 22, and is adapted to ride over the beveled edges 27 of the sliding back-plate 18 and to snap in the notches 26 40 of these sliding back-plates when these notches are properly positioned.

An operating link 38 is fastened to one of the locking bars 28 and terminates in a thumb piece 39. Therefore, when pressure is applied to the thumb piece 39, the link 32 will be rocked, forcing the latches 37 outwardly to free the sliding back-plates 18.

In order to throw the back of the binder open and the binding posts 14 apart, springs 50 40 are provided having each of their ends secured in one of the sliding back-plates 18, respectively. By this construction, when the sliding back-plates are freed by reason of the release of the latch 37 the sliding 55 back-plates 18 will move in opposite directions with respect to one another, carrying the binding posts out of operation or binding position.

I will now proceed to describe the operation 60 of my improved binder. When it is desired to insert the cards or sheets, here indicated by the letter C, the device may be made to assume the position illustrated in Fig. 1. With the cards in position upon one 65 side on the binding posts 14, the other side

or cover, and its corresponding binding posts, will be swung on its hinge until the posts 14 assume a vertical position and are in alignment with apertures of the cards C. The correct position of the binding posts is assured by reason of the angular projections or lips 17, carried by the plate 13. As these lips 17 enter the recesses 20 in the back-plate 18 the motion of the plate 13 and pins 14 is arrested and the pins 14 are 70 in a position to enter the apertures in the cards C. Vertical pressure thereafter applied to the back of the binder will cause the two sliding back-plates 18 to move inwardly toward one another between the locking 75 plates 22. During this action the bevels 27 which are adjacent the notches 26 will force the latches 37 outwardly against the tension of the spring 34 and when the notches 26 come adjacent the latches 37 the spring 34 80 35 will cause these latches to snap into these notches and lock the plates 18 in this closed position. In this position the right-angular lips 17 have passed between the locking plates 22, thereby preventing the plates 13, 90 carrying the pins 14, from being moved on their pivots 16 until the sliding back-plates 18 have been freed and allowed to move sufficiently from between the locking plates 22 to again free the angular lips 17. 95

By this construction, when the pins 14 have entered the apertures in the cards or sheets and the device has been locked, the binding posts or pins 14 will securely retain the cards in place. The device may be unlocked by pressure upon the thumb piece 39 which, by reason of the link 32, will cause both latch bars 28 to move outward simultaneously and lift the latches 37 out of the notches 26 in the sliding back-plates 18. 100 105

It should also be noticed that this binder cannot be made to assume its locking position without the binding posts 14 first having been properly aligned and made to enter the apertures of the cards or sheets C. This 110 is so by reason of the angular projections or lips 17 which will not pass between the locking plates 22 unless entirely housed within the recesses 20 of each of the sliding back-plates 18. In this respect, therefore, 115 the device is what is termed "fool proof" and danger of mutilating the sheets or cards by forcing the non-aligned binding posts together is eliminated.

It should be noted that various changes 120 and modifications may be made in the details of my invention without departing from the spirit and scope thereof and I particularly reserve this right.

Having thus described my invention, what 125 I claim is:

1. A device of the class described comprising side members, a back comprising relatively movable plates for opening and closing said device, post-carrying members 130

hinged to said plates, and straight binding posts carried by said members, said post-carrying members and plates being adapted to coöperate to position said posts in spaced parallel relation when the device is in closed position.

2. A device of the class described comprising side members, a back formed of two relatively movable plates, post-carrying members hingedly secured to said plates, straight binding posts carried by said members, spring means for forcing the plates open and means for automatically locking said device when the same is in closed position.

3. A binder comprising side members and a back, said back being provided with overlapping plates, binding post-carrying members hingedly connected to said plates and secured to said side members, binding posts secured to said post-carrying members, said back and post-carrying members coöperating to position said posts in spaced parallel relation when the device is in closed position, means for locking said device in closed position and means to prevent locking of said device unless said posts are properly aligned.

4. A temporary binder comprising side members, a back including overlapping plates, post-carrying members hingedly secured to said plates and connected to said side members, straight binding posts carried by said post-carrying members, springs normally forcing said overlapping plates apart, means for locking said plates in their extreme overlapping position and means formed on the post-carrying members for preventing the locking of said device unless said binding posts are in proper alinement.

40 5. A device of the class described comprising a pair of side members, a pair of post-carrying members secured thereto, a

back comprising two slidably arranged overlapping plates and locking plates between which said slidable plates are mounted, said post-carrying members being hingedly secured to said overlapping plates, a locking mechanism carried by said locking plates, means upon said slidable plates coöoperating with said locking mechanism for retaining the device in closed position, angular projections formed upon the post-carrying members and recesses formed in the slidable plates for receiving said projections when the device is in locked position.

5. A device of the class described comprising a pair of side members, a pair of post-carrying members secured thereto, a pair of slidable overlapping plates forming a back and hingedly secured to said post-carrying members, straight binding posts projecting from said post carrying members, said plates being slidably arranged to open or close the device, means for locking said plates in their extreme overlapping position and means on said plates and said post-carrying members which coöperate to position said posts in spaced parallel relation when the device is in closed position.

7. A device of the class described comprising a pair of side members, a back formed of two overlapping plates slidable with relation to each other to open or close the device, post-carrying members hingedly secured to said side members, straight binding posts carried by said post-carrying members, spring means normally tending to force said plates open and means for automatically locking said plates in their extreme overlapped position thereby securing the device in closed position and positioning the posts in spaced parallel relation.

WILLIAM FRED DUNNING.
